UNITED STATES PATENT OFFICE.

GEORGE HASKELL SCOTT, OF WORCESTER, MASSACHUSETTS.

APPARATUS FOR HEATING WIRE.

SPECIFICATION forming part of Letters Patent No. 339,219, dated April 6, 1886.

Application filed June 18, 1885. Serial No. 169,027. (No model.)

To all whom it may concern:

Be it known that I, GEORGE HASKELL SCOTT, of Worcester, in the county of Worcester and State of Massachusetts, have invented certain new and useful Improvements 5 in Apparatus for Heating Wire; and I do hereby declare that the following is a full, clear, and exact description of the same, reference being had to the accompanying drawings, forming a part of this specification, and 10 in which—

Figure 1 represents a side view of my heating apparatus, said figure also showing suitable reels and a tempering apparatus in connection with said heating apparatus, as hereinafter more fully described. Fig. 2 represents 15 upon an enlarged scale a vertical transverse section through my improved wire-heating apparatus, taken on line *a b*, Fig. 1, looking 20 in the direction indicated by arrow *c*, same figure; and Fig. 3 represents, also upon an enlarged scale, a vertical central longitudinal 25 section through the heating apparatus aforesaid, also showing in the same figure an ordinary reel, from which the wire is unwound prior to entering said heating apparatus.

My invention relates to apparatus for heating wire for the purpose of annealing and tempering the same; and it consists in passing the 30 wire through a long cylinder or tube in direct contact with burning vaporized petroleum, kerosene, naphtha, or similar inflammable fluids contained therein, said vaporized fluid being supplied to said cylinder or tube and the combustion controlled by suitable means, as 35 hereinafter more fully described.

It also consists in the combination of said heating or annealing apparatus with the ordinary apparatus of reeling and tempering 40 wire.

To enable those skilled in the art to which my invention appertains to make and use the same, I will proceed to describe it more in detail.

In the drawings, A represents the heating 45 apparatus; B, an ordinary reel from which the wire *d* is unwound prior to entering the heating apparatus aforesaid; C, a tempering apparatus, and D a reel for coiling up the finished product.

As said reels and tempering apparatus are of the usual well-known construction and ar-

range ment, a detailed description of the same will be unnecessary in the present instance.

The wire to be treated may be annealed only 55 by passing through the heating apparatus A, and at once coiled up, or it may be both annealed and tempered prior to being coiled by a continuous operation, as shown in Fig. 1 of the drawings. It is heated in the apparatus A 60 by passing through a long cylinder or tube, *e*, containing burning vaporized petroleum, kerosene, naphtha, or similar inflammable fluids. Said cylinder or tube is arranged longitudinally in the center of the upper part of the 65 apparatus. It projects a short distance beyond the outer casing, *f*, and has contracted end openings of the proper size to admit of the wire passing freely through them, and at the same time prevent the escape of the burning 70 flame within. The products of combustion generated in the heating-tube *e* pass off through a flue, *g*, connected therewith. Said tube *e* is inclosed and supported in a fire-brick casing, *h*, resting on a horizontal iron plate, *i*, which 75 extends over the whole size of the apparatus, and is in turn supported at the edges thereof by the outer casing, *f*. A division is thereby formed between the upper part of the apparatus, containing the inflammable fluid under 80 combustion, and its lower part, where said fluid is stored, as hereinafter described.

Portions of the fire-brick casing *h* are left open, as shown at the points *h'*, for the purpose of providing a means whereby the ends of the 85 supply-pipes and their regulating devices may be conveniently reached from the outside of the apparatus. The side of the outer casing, *f*, corresponding therewith is also provided with openings *f'* for the same purpose.

The supply of vaporized fluid is admitted to the inside of tube *e* through a suitable number of openings, *e'*, formed in the side thereof, as shown in Figs. 2 and 3. In this instance I have shown four of such inlet-openings; but, 95 if desired, a greater or less number may be employed, to suit different requirements.

I have represented in connection with each of the inlets *e'* of the tube *e* a device for vaporizing the fluid used similar to an ordinary 100 atomizer used for toilet purposes, the fluid *j*, contained in the reservoir *k*, being drawn up through the pipes *l* and vaporized as it passes out at their upper ends by forcing a strong

steady current of air or steam across said upper openings through the branch nozzles *m* of the main air or steam supply pipe *n*, said steam or air also facilitating the process of 5 combustion in the tube *e*. To further facilitate said process of combustion, I extend the supply-pipe *n* up through the exhaust smoke-flue *g*, thereby heating the air or steam contained therein before being expelled from the 10 nozzles *m*, as aforesaid, thus at the same time utilizing the waste heat of the apparatus in addition to the above-described advantage.

The reservoir *k*, which in this instance is made round in cross-section, as shown in Fig. 15 2, is supported a little above the bottom of the apparatus, and is surrounded with a body of running water, *e*², which enters through the pipe *o*, near the bottom of the apparatus, and flows out of the pipe *p*, upon the opposite side 20 of said apparatus, a short distance above the level of the top of the reservoir. By thus surrounding the inflammable fluid *j* with cool running water there is but little if any danger of its igniting from the heat produced above 25 in the tube *e*, hereinbefore described, and to further reduce the liability to danger from the above cause openings *q* are formed on opposite sides of the outer casing, *f*, just under the horizontal plate *i*, thus admitting of a free 30 circulation of cool fresh air between said plate and the top of the water surrounding the inflammable fluid *j* in the reservoir *k*. Said fluid *j* is supplied to the reservoir through a suitable inlet-pipe, *r*.

35 By increasing or decreasing the number of inlets *e*' in tube *e* and the atomizers connected therewith the degree of heat around the wire passing through said tube may be correspondingly regulated. The degree of combustion 40 may also be regulated more or less by opening or closing valves *s*, interposed between the nozzles *m* and air or steam supply pipe *n*, more or less of the inflammable liquid *j* in reservoir *k* being drawn up, according to the volume and velocity of the air or steam current 45 across the top openings of the pipes *l*.

The valves *s*, which may be of ordinary well-known construction, are operated by means of the hand-wheels *t* on the outer ends of the rods 50 *u*, whose inner ends are connected with said valves.

The tube *e* may be made of metal, as shown, or any other suitable materials.

Those skilled in the art to which my invention appertains will readily perceive from the foregoing description and the accompanying drawings that by its application to practice many objectionable features are entirely removed.

60 By simply turning on the air or steam pressure in the manner hereinbefore described and lighting the vaporized fluid the apparatus is in a very few moments under full blast with the flame at its maximum heat, while at the 65 same time being under perfect control of the

operator. After the work in hand is completed the operator then turns off the pressure aforesaid, when the expense ceases, thus not only economizing in fuel, but also saving unnecessary burning out of the apparatus.

Another advantage of my improved apparatus is that the quality of the wire thus heated is much superior to that produced by the usual methods employed, especially when lead is used, which often contains more or less impurities injurious to iron and steel, thus causing the production of much wire of inferior quality.

Having described my improved process for heating wire, what I claim therein as new and 80 of my invention, and desire to secure by Letters Patent, is—

1. In a furnace for heating wire, the outside casing, *f*, having the horizontal division-plate *i*, and side openings *f*' *q*, the fire-brick 85 casing *h*, provided with side openings *h*', and chimney *g*, in combination with the horizontal tube *e*, having openings at both ends thereof and provided with side openings *e*', the conducting-pipes *l*, reservoir *k*, and supply-pipes 90 *n*, provided with nozzles *m*, and ordinary regulating-valves, *s*, all constructed and arranged substantially as shown and described.

2. The combination of the reels *B* *D*, the outside casing, *f*, having the horizontal division-plate *i*, and side openings *f*' *q*, the fire-brick casing *h*, provided with side openings *h*', and chimney *g*, with the horizontal tube *e*, having openings at both ends thereof and provided with side openings *e*', the conducting-pipes *l*, reservoir *k*, and supply-pipes *n*, provided with nozzles *m*, and ordinary regulating-valves, *s*, substantially as and for the purposes set forth.

3. The combination of the reel *B*, an ordinary 105 tempering apparatus, *C*, reel *D*, the outside casing, *f*, having the horizontal division-plate *i*, and side openings *f*' *q*, the fire-brick casing *h*, provided with side openings *h*', and chimney *g*, with the horizontal tube *e*, having openings at both ends thereof and provided with side openings *e*', the conducting-pipes *l*, reservoir *k*, and supply-pipes *n*, provided with nozzles *m*, and ordinary regulating-valves, *s*, substantially as and for the purposes set forth. 110

4. The combination of the tube *e*, having openings at both ends thereof and provided with side openings *e*', outside casing, *f*, fire-brick casing *h*, having side openings *h*', and chimney *g*, with the supply-pipes *n*, provided 120 with nozzles *m*, with ordinary regulating-valves, *s*, and extending from one end of said tube to the other, in close proximity thereto, and thence up through the inside of the chimney *g*, substantially as shown and described, 125 for the purpose stated.

GEO. HASKELL SCOTT.
